United States Patent Office.

LOUIS F. VIENOT, OF NEW YORK, N. Y.

Letters Patent No. 101,790, dated April 12, 1870.

IMPROVED COUNTER AND SHOW-CASE.

The Schedule referred to in these Letters Patent and making part of the same

To all whom it may concern:

Be it known that I, LOUIS F. VIENOT, of the city, county, and State of New York, have invented a new and useful Improvement in Combined Counter and Show-Case; and I do hereby declare that the following is a full, clear, and exact description thereof, which will enable others skilled in the art to make and use the same, reference being had to the accompanying drawing forming part of this specification.

Figure 1 represents a front elevation of my combined counter and show-case.

Figure 2 is a vertical transverse section of the same.

Similar letters of reference indicate corresponding parts.

The object of this invention is to reduce the cost of counters and show-cases by combining them, and thereby saving the expensive counter tops.

At present show-cases are made separate and placed upon the counters, on which they do not stand very firm, destroying, as they are moved, the finish on the counter tops.

A, in the drawing, represents the counter, and

B the show-case.

The latter is firmly fitted thereto, without requiring any prolongation of the top plate of the counter beneath it.

The ordinarily expensive finish on the top of the counter is thus made unnecessary, and the expense is thereby so reduced that the addition of the show-case will hardly add to the cost of the counter.

Another advantage of this arrangement is that the show-case may be lowered in the counter, as in fig. 1, to have its bottom below the regular top b of the counter.

Having thus described my invention,

I claim as new and desire to secure by Letters Patent—

The counter A and show-case B, relatively constructed, adjusted, and fitted together, as set forth.

LOUIS F. VIENOT.
